RAILWAY BRAKING APPARATUS

John W. Logan, Jr., Wilkinsburg, Pa., assignor to
The Union Switch & Signal Company, Swiss-
vale, Pa., a corporation of Pennsylvania

Application February 17, 1933. Serial No. 657,204

27 Claims. (Cl. 303—20)

My invention relates to railway braking apparatus, and particularly to braking apparatus of the type comprising wheel engaging braking bars located beside a track rail, and movable toward and away from the rail into braking and non-braking positions. More particularly my invention relates to apparatus of the type described wherein the braking bars are arranged to be moved to their braking positions by means of one or more fluid pressure operated motors and to be restored to their non-braking positions by suitable biasing means such as gravity.

Specifically, my invention relates to means for controlling the supply of fluid pressure to, and exhaust of fluid pressure from, the fluid pressure motor or motors of braking apparatus of the type described when the braking apparatus is to be utilized in connection with a Duplex pressure fluid distribution system such as is disclosed and claimed in an application for Letters Patent of the United States, Serial No. 639,434, filed by Herbert L. Bone, on Oct. 25, 1932, and one object of my invention is to improve and simplify the control means disclosed in the said Bone application.

Other objects of my invention will appear as the description proceeds.

The control means set forth in my present application are somewhat similar to the control means set forth in the copending application for Railway braking apparatus, Serial No. 657,210, filed by H. L. Bone and myself on the same day as the present application, and the said copending application contains claims which cover broadly certain features of the invention described in my present application.

I will describe two forms of apparatus embodying my invention, and will then point out the novel features thereof in claims.

In the accompanying drawings, Fig. 1 is a diagrammatic view illustrating one form of apparatus embodying my invention. Fig. 2 is a similar view illustrating a modified form of the apparatus shown in Fig. 1.

Similar reference characters refer to similar parts in both views.

Referring to the drawings, the reference character 1 designates one track rail of a stretch of railway track, which track rail, as here shown, is secured to a rail support 2 mounted on an adjacent pair of the usual crossties 3, only one crosstie being visible in the drawings. Associated with the rail 1 is a car retarder comprising two braking bars A¹ and A² located on opposite sides 55 of the rail. Each of these braking bars com-

prises as usual, a brake beam 4 and a brake shoe 5.

The braking bars are arranged to be moved toward and away from the rail 1 by means of a lever 6 which is pivotally mounted at one end on a pivot pin 8 carried by the rail support 2, and a lever 7 which is pivotally mounted intermediate its ends on the pivot pin 8. The lever 6 is inclined upwardly and extends away from the rail 1, and is provided in its upper surface with a groove 6^a which receives the braking bar A¹. The one end 7^a of the lever 7 is likewise inclined upwardly and extends away from the rail 1 at the opposite side of the rail from the lever 6, and the other end 7^b of the lever 7 is inclined downwardly and extends away from the rail 1 below the lever 6. The end 7^a of the lever 7 is provided in its upper surface with a groove 7^c, similar to the groove 6^a in the lever 6, which groove receives the braking bar A². The parts are so arranged and so proportioned that if the outer or free ends of the levers 6 and 7 are moved apart, the braking bars will be moved toward the rail 1 into their effective or braking positions. When the braking bars occupy their braking positions, the brake shoes 5 will engage

the opposite side faces of a car wheel traversing rail 1 and will retard the speed of the car. The center of gravity of the lever 6 and braking bar A¹ is considerably to the right of the pivot pin 8 so that this lever will normally tend to rotate in a clockwise direction about the pivot pin. Similarly, the center of gravity of the lever 7 and braking bar A² is to the left of the pivot pin 8, so that this lever will normally tend to rotate in a counterclockwise direction about the pivot pin 8. It will be apparent, therefore, that when no force is applied to the free ends of the levers 6 and 7 to move them apart, the free ends of the levers will move toward each other, thereby moving the braking bars to their ineffective or non-braking positions in which they are illustrated in the drawings.

The levers 6 and 7 are arranged to be moved apart to move the braking bars to their braking positions by means of a fluid pressure motor M comprising a cylinder 9 containing a reciprocable piston 10 attached to a piston rod 11. The cylinder 9 is pivotally connected with the free end of the lever 6 by means of trunnions 12 formed on the side of the cylinder and extending through bifurcations 13 formed on the lever 6, while the piston rod 11 is connected at its free end with the free end 7^b of the lever 7 by means of an adjustable eyebolt 14 and pivot pin 15. Fluid pressure may be admitted to the cylinder 9 be-

tween the upper end of the cylinder and the piston 10 through an opening 16 which is threaded to receive a pipe 17. When fluid pressure is admitted to the cylinder 9 through the opening 16 and pipe 17, the cylinder 9 will be forced upwardly and the piston 10 downwardly, thereby separating the levers 6 and 7, and hence moving the braking bars toward their effective or braking positions. It will be obvious that when the 10 braking bars are moved to their braking positions, they will exert a braking force which is proportional to the pressure of the fluid supplied to the cylinder 9.

It should be pointed out that while I have 15 shown only one operating unit for the braking bars A¹ and A² in the drawings, in actual practice these braking bars will be provided with a plurality of other similar units, disposed at spaced intervals along the bars, substantially as 20 shown in an application for Letters Patent of the United States Serial No. 516,883, filed by Herbert L. Bone, on February 19, 1931, for Railway braking apparatus. It should also be pointed 25 out, that as a general rule, the car retarder will consist not only of braking bars associated with one track rail of a stretch of railway track, as shown in the drawings, but also of other similar braking bars associated with the opposite track rail as well, the length of the braking bars 30 associated with both track rails being determined by the speed and the weight of the cars, to be retarded, the lengths of the cars, the number of wheels on the cars, etc.

The motor M is controlled by three magnet 35 valves designated by the reference characters V¹, V² and V³, respectively, and each comprising a valve stem 18 biased to an upper position by means of a spring 19, and provided with a winding 20 and an armature 21. When valve V¹ is 40 energized, as shown in the drawings, valve stem 18 of this valve moves downwardly against the bias exerted by the associated spring 19, and under these conditions, a pipe 22 which 45 communicates with the pipe 17 is connected with atmosphere through a port 23, thus connecting the upper end of cylinder 9 with atmosphere. When valve V¹ is deenergized, however, valve stem 18 of this valve is moved upwardly by the associated spring 19, and pipe 22 is then disconnected 50 from port 23 so that the upper end of cylinder 9 is then disconnected from atmosphere. When valve V² is energized, valve stem 18 of this valve moves downwardly and pipe 22 is then connected 55 with a pipe 24 forming part of a low pressure distribution system. This low pressure distribution system is constantly supplied with fluid pressure, usually air, from a relatively low pressure source not shown in the drawings, and it follows that when valve V² is energized, the upper end of cylinder 9 is supplied with fluid pressure from the low pressure system. When valve 60 V² is deenergized, however, pipe 22 is disconnected from pipe 24, and is connected with a pipe 25 which leads to the valve V³. When valve V³ is energized, valve stem 18 of this valve moves 65 downwardly and connects pipe 25 with a pipe 26 forming part of a high pressure distribution system, which latter system is constantly supplied with fluid pressure, usually air, from a relatively high pressure source. It will be seen, therefore, that when valve V³ is energized, if valve V² is then deenergized, the upper end of cylinder 9 will be supplied with fluid pressure from the high pressure system. When valve V³ 70 is deenergized, however, valve stem 18 of this

valve moves to its upper position, and pipe 26 is then disconnected from pipe 25, so that the supply of fluid pressure from the high pressure system to cylinder 9 is cut off.

The pressure of the fluid in the low pressure system may be maintained at any suitable pressure, but for purposes of illustration, I will assume that this pressure is maintained at approximately 50 pounds per square inch. Likewise, the pressure of the fluid in the high pressure system may be maintained at any desired pressure, but for purposes of illustration, I will assume that this pressure is maintained at approximately 100 pounds per square inch.

The valves V are controlled in part by two pressure responsive devices P²⁰⁻³⁰ and P⁷⁰⁻⁸⁰, each comprising a Bourdon tube 27 connected to the pipe 17, and hence subjected to the pressure of the fluid in the upper end of cylinder 9 of motor M. Each Bourdon tube 27 controls two contacts 28—28^a and 28—28^b. The pressure responsive devices P²⁰⁻³⁰ and P⁷⁰⁻⁸⁰ are so constructed that they will operate successively as the pressure in the upper end of cylinder 9 increases. For example, for all pressures below 20 pounds per square inch, contact 28—28^a of each of these devices is closed. If the pressure exceeds 20 pounds per square inch, however, contact 28—28^a of pressure responsive device P²⁰⁻³⁰ opens, and if the pressure exceeds 30 pounds per square inch, contact 28—28^b of device P²⁰⁻³⁰ closes. In similar manner, the pressure responsive device P⁷⁰⁻⁸⁰ is adjusted to open its contact 28—28^a at 70 pounds per square inch, and to close contact 28—28^b at 80 pounds per square inch. Of course, these specific pressures are not essential, but are only mentioned for purposes of explanation.

The valves V are also controlled by means of two relays B and C of the ordinary quick-acting type, which relays, in turn, are controlled by a pressure responsive device P⁴⁰⁻⁶⁰. This latter pressure responsive device is similar in all respects to the previously described pressure responsive devices P²⁰⁻³⁰ and P⁷⁰⁻⁸⁰, with the exception that this device is so adjusted that it will open its contact 28—28^a when the pressure of the fluid in the upper end of cylinder 9 of motor M increases to a pressure which is a predetermined amount below the pressure of the fluid in the low pressure system, and will close its contact 28—28^b when the pressure of the fluid in the upper end of cylinder 9 of motor M increases to a pressure which is a predetermined amount above the pressure of the fluid in the low pressure system. For example, for purposes of illustration I will assume 130 that the device P⁴⁰⁻⁶⁰ is so adjusted that it will open its contact 28—28^a when the pressure of the fluid in the upper end of cylinder 9 of motor M increases to 40 pounds per square inch, and will close its contact 28—28^b when the pressure in the 135 upper end of the cylinder 9 of motor M increases to 60 pounds per square inch.

The control of the relays B and C by the pressure responsive device P⁴⁰⁻⁶⁰ is such that when contact 28—28^a of this device is closed, a circuit will be completed for relay B, and when contact 28—28^b of this pressure responsive device is closed, a circuit will be completed for relay C. The circuit for relay B passes from one terminal of a suitable source of current, here shown as a battery D, through wires 30, 31, 32 and 33, a line wire 34, the winding of relay B, wire 35, contact 28—28^a of pressure responsive device P⁴⁰⁻⁶⁰, wires 36, 37 and 38, and line wire 39 back to battery D. The circuit for relay C passes from battery D, 140

- through wires 30, 31, 32 and 33, line wire 34, the winding of relay C, wire 40, contact 28-28^b of pressure responsive device P⁴⁰⁻⁶⁰, wires 36, 37 and 38, and line wire 39 back to battery D. It will be apparent, therefore, that when the pressure of the fluid in motor M is below 40 pounds per square inch, relay B will be energized, and that when the pressure of the fluid in motor M is above 60 pounds per square inch, relay C will be energized, but that when the pressure of the fluid in motor M is between 40 and 60 pounds per square inch, the relays B and C will both be deenergized.
- The valves V are further controlled by means of a manually operable lever L which as here shown, is capable of assuming five positions, indicated by dotted lines in the drawings and designated by the reference characters p¹ to p⁵, inclusive. The lever L controls a plurality of contacts each designated by the reference character 29 with a distinguishing exponent corresponding to the position of the lever in which the associated contact is closed. For example, contact 29¹ is closed in the p¹ position of the lever, contact 29² in the p² position of the lever, etc.
- 25 Lever L will usually be located at a point remote from the braking apparatus, as in the control cabin of a classification yard car retarder system, and will be connected with the braking apparatus by means of line wires extending from the control cabin to the braking apparatus.
- As shown in the drawings, lever L occupies its p¹ or "off" position, which is the position which it normally occupies when no cars are to be retarded. Contact 29¹ of the lever is therefore closed, while all of the remaining contacts are open. Relay B is energized and relay C is deenergized. Since relay C is deenergized, and contact 29¹ of lever L is closed, a circuit is completed for valve V¹, and current flows from battery D through wires 30, 31, 32 and 33, contact 29¹ of lever L, line wire 41, wires 42 and 43, back contact 44-44^b of relay C, wire 45, winding 20 of valve V¹, wires 37 and 38, and line wire 39 back to battery D. Valve V¹ is therefore energized, so that the upper end of motor M is vented to atmosphere. The valves V² and V³ are both deenergized, and the supply of fluid to motor M from both the high and low pressure systems is accordingly cut off. Since the supply of fluid to motor M is cut off and the motor is vented to atmosphere, the braking bars are held by gravity in their non-braking positions, in which positions they are shown in the drawings. Furthermore, since the supply of fluid to motor M is cut off, and the motor is vented to atmosphere, the contact 28-28^a of each of the pressure responsive devices P is closed, and the contact 28-28^b of each of these devices is open.
- 60 I will now assume that the operator wishes to make a comparatively light brake application. To do this, he will move lever L from its p¹ to its p² position. This movement of the lever will interrupt the circuit which was previously closed for valve V¹, and will complete a circuit for valve V², which latter circuit passes from battery D through wires 30, 31, 32 and 45, contact 29² of lever L, line wire 46, contact 28-28^a of pressure responsive device P²⁰⁻³⁰, wire 47, front contact 48-48^a of relay B, wires 49 and 50, winding 20 of valve V², wire 38, and line wire 39 back to battery D. Valve V¹ will therefore become deenergized and valve V² will become energized. The deenergization of valve V¹ will disconnect motor M from atmosphere, while the energiza-
- tion of valve V² will admit fluid to the motor from the pipe 24, thus causing the braking bars to move to their effective or braking positions. When the pressure of the fluid in motor M increases to 20 pounds per square inch, contact 28-28^a of pressure responsive device P²⁰⁻³⁰ will open and will deenergize valve V², thus cutting off any further supply of fluid to motor M as long as the pressure of the fluid in the motor remains above 20 pounds per square inch. If the pressure of the fluid in motor M now increases to 30 pounds per square inch for any reason, a circuit will become completed for valve V¹, and valve V¹ will become energized and will exhaust fluid from motor M. The circuit which will become completed for valve V¹ under these conditions passes from battery D through wires 30, 31, 32 and 45, contact 29² of lever L, line wire 46, contact 28-28^b of pressure responsive device P²⁰⁻³⁰, wires 42 and 43, back contact 44-44^b of relay C, wire 45, winding 20 of valve V¹, wires 37 and 38, and line wire 39 back to battery D. Valve V¹ will remain energized under these conditions, and will continue to vent fluid from motor M until the pressure of the fluid again decreases sufficiently to permit contact 28-28^b of pressure responsive device P²⁰⁻³⁰ to open and deenergize valve V¹. It will be apparent, therefore, that when lever L occupies its p² position, the braking bars will be held in their braking positions by a pressure of between 20 and 30 pounds per square inch. It will also be apparent that the fluid which is supplied to motor M to move the braking bars to their braking positions is supplied entirely from the low pressure system.
- I will next assume that the operator wishes to cause the braking bars to exert a somewhat higher braking force. He will therefore move lever L to its p³ position. In this position of the lever, all of the previously described circuits for the valves V¹ and V² will be interrupted, and another circuit will be completed for valve V², which latter circuit passes from battery D through wire 30, contact 29³ of lever L, line wire 51, wires 49 and 50, winding 20 of valve V², wire 38, and line wire 39 back to battery D. Valve V² will therefore now become energized and since the circuit over which it becomes energized is controlled solely by contact 29³ of lever L, this valve will subsequently remain energized as long as lever L remains in its p³ position, so that fluid will now be supplied to motor M from the low pressure source until the pressure of the fluid in the motor builds up to that of the low pressure source. It will be apparent, therefore, that when lever L occupies its p³ position, the braking bars will be held in their braking positions by fluid at the full pressure of the low pressure source, which pressure it will be remembered is approximately 50 pounds per square inch. It will be noted that since the pressure of the fluid in motor M is now approximately 50 pounds per square inch, contact 28-28^a of pressure responsive device P⁴⁰⁻⁶⁰ will become opened, thus deenergizing relay B. The deenergization of relay B under these conditions, however, will have no effect upon the remainder of the apparatus.
- I will now assume that lever L occupies its p³ position and that the operator in order to cause the braking bars to exert a still higher braking force moves lever L to its p⁴ position. Under these conditions, valve V³ will become energized over a circuit which passes from battery D

through wires 30, 31, 32 and 45, contact 29⁴ of lever L, line wire 52, contact 28—28^a of pressure responsive device P⁷⁰⁻⁸⁰, wires 53 and 47, back contact 48—48^b of relay B, wire 54, winding 20 of valve V³, and line wire 39 back to battery D. The energization of valve V³ will admit fluid to motor M from pipe 26 until the pressure of the fluid in the motor builds up to 70 pounds per square inch, at which time contact 28—28^a of pressure responsive device P⁷⁰⁻⁸⁰ will open, and will de-energize valve V³. As soon as the pressure of the fluid in motor M has increased to 60 pounds per square inch, contact 28—28^b of pressure responsive device P⁴⁰⁻⁶⁰ will become closed, which will cause relay C to become energized. The energization of relay C under these conditions, however, will have no effect on the apparatus unless the pressure in motor M now increases to 80 pounds per square inch, whereupon the resultant closing of contact 28—28^b of pressure responsive device P⁷⁰⁻⁸⁰ will complete another circuit for valve V², and current will then flow from battery D through wires 30, 31, 32 and 45, contact 29⁴ of lever L, line wire 52, contact 28—28^b of pressure responsive device P⁷⁰⁻⁸⁰, wire 43, front contact 44—44^a of relay C, wire 50, winding 20 of valve V², wire 38, and line wire 39 back to battery D. When this latter circuit for valve V² becomes closed, valve V² will become energized and will connect the motor M with the pipe 24, and since the pressure of the fluid in the motor will then be above that of the fluid in the pipe 24, fluid will be vented from the motor into the pipe, and hence into the low pressure distribution system, where it can be again utilized as conditions require.

I will now assume that the operator, instead of moving lever L to its p⁴ position from its p³ position, moves the lever to its p⁴ position directly from its p¹ position. Under these conditions, relay B will initially be energized and relay C will initially be deenergized. As a result, when the lever reaches its p⁴ position, a circuit for valve V² will become closed over which current will flow from battery D through wires 30, 31, 32 and 45, contact 29⁴ of lever L, line wire 52, contact 28—28^a of pressure responsive device P⁷⁰⁻⁸⁰, wires 53 and 47, front contact 48—48^a of relay B, wires 49 and 50, winding 20 of valve V², wire 38, and line wire 39 back to battery D. Valve V² will therefore become energized and will admit fluid pressure to motor M in the manner previously described. When the pressure of the fluid in motor M increases to 40 pounds per square inch, contact 28—28^a of pressure responsive device P⁴⁰⁻⁶⁰ will open and will deenergize relay B, thus causing relay B to open its front contact 48—48^a and to close its back contact 48—48^b. The opening of front contact 48—48^a of relay B will interrupt the circuit just traced for valve V², while the closing of back contact 48—48^b of relay B will complete the previously described circuit for valve V³ including this contact. Valve V² will therefore now become deenergized and valve V³ will become energized. When valve V³ becomes energized, the apparatus will subsequently function in the same manner as it did after this valve became energized when lever L was moved to its p⁴ position from its p³ position. It will be apparent, therefore, that when lever L is moved directly from its p¹ to its p⁴ position, valve V² will first become energized and will admit fluid pressure from the low pressure system to motor M until the pressure in the motor increases to 40 pounds per square inch, after which valve V² will become deenergized

and valve V³ will become energized. When valve V³ becomes energized any further fluid which is supplied to motor M will of course be supplied from the high pressure distribution system.

I will next assume that lever L is in its p⁴ position and that the operator desires to cause the braking bars to exert their maximum braking force. He will therefore move lever L to its p⁵ position. Under these conditions, relay B will be deenergized when the lever reaches its p⁵ position and the movement of lever L to its p⁵ position will therefore complete a circuit for valve V³ which passes from battery D through wires 30 and 31, contact 29⁵ of lever L, line wire 55, back contact 48—48^b of relay B, wire 54, winding 20 of valve V³, and line wire 39 back to battery D. Valve V³ will therefore become energized and will subsequently remain energized, thus permitting the pressure of the fluid in motor M to build up to the full pressure of the high pressure source, so that the braking bars will exert their maximum braking force.

I will now assume that lever L occupies its p⁵ position so that the braking bars are exerting their maximum braking force, and that the operator wishes to decrease the braking force exerted by the braking bars to that corresponding to the p² position of the lever. The operator will therefore move the lever to its p² position. This movement of the lever will interrupt the circuit which was previously closed for valve V³ and this valve will therefore become deenergized, thus cutting off the supply of fluid pressure to motor M from the high pressure source. Furthermore, since relay C is initially energized under these conditions, this movement of lever L will complete the previously described circuit for valve V² including contact 28—28^b of pressure responsive device P²⁰⁻³⁰ and front contact 44—44^a of relay C, and valve V² will therefore become deenergized and will connect motor M with pipe 24, and hence with the low pressure distribution system. When the motor becomes connected with the pipe 24, the pressure of the fluid in the motor will, of course, be above that of the fluid in the low pressure system, and fluid from the motor will therefore be vented into the low pressure system until the pressure decreases to 60 pounds per square inch. When this happens, contact 28—28^b of pressure responsive device P⁴⁰⁻⁶⁰ will open and will deenergize relay C, and the deenergization of this relay, in turn, will interrupt the circuit which was previously closed for valve V² at front contact 44—44^a of this relay and will also complete the previously traced circuit for valve V¹ including contact 28—28^b of pressure responsive device P²⁰⁻³⁰ and back contact 44—44^b of relay C. Valve V² will therefore become deenergized and valve V¹ will become energized. The deenergization of valve V² will prevent further exhaust of fluid pressure from motor M into the low pressure system, while the energization of valve V¹ will vent fluid from the motor to atmosphere. When the pressure of the fluid in motor M decreases to 40 pounds per square inch, contact 28—28^a of pressure responsive device P⁴⁰⁻⁶⁰ will become closed and will energize relay B. After relay B becomes energized, the apparatus will then function in the same manner as it did when the lever L was moved from its p¹ to its p² position.

I will next assume that lever L occupies its p⁶ position so that the braking bars are exerting their maximum braking force and that the operator, wishing to restore the braking bars to their ineffective or non-braking positions, moves lever

L to its p^1 position. Under these conditions, valve V^3 will become deenergized and valve V^2 will initially become energized over a circuit which passes from battery D through wires 30, 31, 5 32 and 33, contact 29¹ of lever L, line wire 41, wires 42 and 43, front contact 44—44^a of relay C, wire 50, winding 20 of valve V^2 , wire 38, and line wire 39 back to battery D. The energization of valve V^2 will connect motor M with pipe 24 of 10 the low pressure distribution system, and since the pressure of the fluid in motor M will then be above that in pipe 24, fluid will be vented from the motor into pipe 24. When the pressure of the fluid in the motor decreases to 60 pounds per 15 square inch, contact 28—28^b of pressure responsive device P^{40-60} will open and will deenergize relay C, thereby deenergizing valve V^2 . The deenergization of relay C will also complete the 20 previously described circuit for valve V^1 including contact 29¹ of lever L and back contact 44—44^b of relay C, so that valve V^1 will now become energized and will exhaust fluid from motor M to atmosphere. When the pressure of the fluid in motor M decreases to 40 pounds per 25 square inch, contact 28—28^a of pressure responsive device P^{40-60} will become closed and will energize relay B. The energization of relay B under these conditions, however, will have no effect on the remainder of the braking apparatus. 30 As the pressure of the fluid in motor M decreases, the braking bars will return to their braking positions by gravity, and when the braking bars reach their full braking positions, all the parts will then be restored to the positions in which 35 they are shown in the drawings.

It should be particularly pointed out that while in the foregoing description, I have described the operation of the apparatus for only a few of the possible movements of lever L, the operation of the apparatus for the remainder of the movements of the lever is similar to that already described, and it is believed that this operation will be understood from an inspection of the drawings and from the foregoing description without further detailed explanation.

Referring now to Fig. 2, as here shown, the relays B and C instead of being located at the retarder as shown in Fig. 1, are located at the control point, and rectifiers have been provided 50 to decrease the number of line wires required between the control point and the braking apparatus. Furthermore, lever L has been provided with two additional contacts 29¹⁻² and 29⁴⁻⁵, the contact 29¹⁻² being closed in the p^1 and p^2 positions of the lever as well as in any position of the lever intermediate these two positions; and the contact 29⁴⁻⁵ being closed in the p^4 and p^5 positions of the lever, and in any position of the lever intermediate these two positions. The 55 remainder of the apparatus here shown is similar to that shown in Fig. 1.

With the apparatus constructed as here shown, when the pressure of the fluid in motor M is below 40 pounds per square inch, so that contact 60 28—28^a of pressure responsive device P^{40-60} is closed, relay B will become energized over a circuit which passes from a battery E, through wires 56 and 57, winding of relay B, an asymmetric unit 58 in its low resistance direction, line wire 59, contact 28—28^a of pressure responsive device P^{40-60} , wire 60, line wire 62, and wire 63 back to battery E. Furthermore, with the apparatus constructed as here shown, when the pressure of the fluid in cylinder 9 in motor M 65 is above 60 pounds, so that contact 28—28^b of

pressure responsive device P^{40-60} is closed, relay C will then become energized over a circuit which passes from battery D through wires 65 and 66, line wire 67, contact 28—28^b of pressure responsive device P^{40-60} , line wire 59, an asymmetric unit 69 in its low resistance direction, winding of relay C, and wires 57 and 56 back to battery D. When the pressure of the fluid in motor M is between 40 and 60 pounds per square inch, however, the circuits just traced for the relays B and C will both be open, and these relays will of course be deenergized.

The operation of the apparatus shown in Fig. 2, as a whole, is as follows: When lever L occupies its p^1 or "off" position, as shown in the drawings, relay B is energized and relay C is deenergized. Valve V^1 is energized over a circuit which passes from battery D through wires 65 and 66, contact 29¹ of lever L, wires 70, 71 and 72, an asymmetric unit 73 in its lower resistance direction, back contact 48—48^b of relay C, line wire 74, an asymmetric unit 75 in its low resistance direction, winding 20 of valve V^1 , wire 76, line wire 77, and wire 56 back to battery D. The valves V^2 and V^3 are both deenergized. Since valve V^1 is energized, cylinder 9 of motor M is vented to atmosphere, and since valves V^2 and V^3 are deenergized, the supply of fluid to cylinder 9 of motor M from both the high and low pressure systems is cut off. The 105 braking bars are therefore held in their braking positions by gravity. Furthermore, since cylinder 9 of motor M is vented to atmosphere, and the supply of fluid from both the high and low pressure systems to the cylinder is cut off, the contact 28—28^a of each of the pressure responsive devices P is closed and the contact 28—28^b of each of these pressure responsive devices is open.

Assuming now that lever L is moved from its p^1 or "off" position to its p^2 position, valve V^1 will become deenergized, and valve V^2 will become energized, the circuit for valve V^2 under these conditions passing from battery E through wire 56, line wire 77, wire 76, winding 20 of valve V^2 , line wire 78, wire 79, contact 29¹⁻² of lever L, wire 80, front contact 44—44^a of relay B, an asymmetric unit 81 in its low resistance direction, wires 72, 71 and 85, contact 29² of lever L, line wire 82, contact 28—28^a of pressure responsive device P^{20-30} , line wire 62, and wire 63 back to battery E. The deenergization of valve V^1 disconnects the cylinder 9 of motor M from atmosphere, while the energization of valve V^2 connects the motor with the low pressure source, thus causing the braking bars to be moved to their braking positions. When the pressure of the fluid in cylinder 9 increases to 20 pounds per square inch, contact 28—28^a of pressure responsive device P^{20-30} will open and will deenergize valve V^2 , and if the pressure of the fluid in motor M increases to 30 pounds per square inch, contact 28—28^b of pressure responsive device P^{20-30} will close and will complete another circuit for valve V^1 . This latter circuit for valve V^1 may be traced from battery D through wires 65 and 66, line wire 67, wire 53, contact 28—28^b of pressure responsive device P^{20-30} , line wire 82, contact 29² of lever L, wires 85, 71 and 72, asymmetric unit 73 in its low resistance direction, back contact 48—48^b of relay C, line wire 74, asymmetric unit 75 in its low resistance direction, winding 20 of valve V^1 , wire 76, line wire 77, and wire 56 back to battery D. It follows, therefore, that when lever 140

145 lever L is moved from its p^2 position to its p^1 position, valve V^1 will become energized over a circuit which passes from battery D through wires 65 and 66, line wire 67, contact 28—28^b of pressure responsive device P^{20-30} , line wire 82, contact 29² of lever L, wires 85, 71 and 72, asymmetric unit 73 in its low resistance direction, back contact 48—48^b of relay C, line wire 74, asymmetric unit 75 in its low resistance direction, winding 20 of valve V^1 , wire 76, line wire 77, and wire 56 back to battery D. It follows, therefore, that when lever 150

L is moved from its p^1 to its p^2 position, cylinder 9 of motor M will be supplied with fluid from the low pressure source as long as the pressure of the fluid in the cylinder is below 20 5 pounds per square inch, and if the pressure of the fluid in the cylinder exceeds 30 pounds per square inch, the fluid in the cylinder will be vented to atmosphere.

If the operator moves lever L to its p^3 position, valve V^2 will become energized over a circuit which remains continuously closed as long as lever L remains in its p^3 position, this circuit passing from battery D through wire 65, contact 29³ of lever L, line wire 78, winding 20 of valve 15 V^2 , wire 76, line wire 77, and wire 56 back to battery D. Under these conditions, therefore, cylinder 9 will be continuously supplied with fluid from the low pressure system, so that the fluid in the motor will build up to the full pressure 20 of this system. As was previously pointed out, the fluid in the low pressure system is maintained at a pressure of approximately 50 pounds per square inch, so that some time after lever L is moved to its p^3 position, contact 28-28^a of 25 pressure responsive device P^{40-60} will open and will deenergize relay B. The deenergization of this relay, however, will have no effect on the apparatus as long as lever L remains in its p^3 position.

If, now, lever L is moved from its p^3 position to its p^4 position, valve V^2 will become deenergized, and valve V^3 will become energized, the circuit over which valve V^3 becomes energized passing from battery E through wire 56, line 30 wire 77, winding 20 of valve V^3 , an asymmetric unit 84, in its low resistance direction, line wire 74, back contact 44-44^b of relay B, asymmetric unit 81 in its low resistance direction, wires 72, 35 71 and 85, contact 29⁴ of lever L, line wire 86, 40 contact 28-28^a of pressure responsive device P^{70-80} , wire 61, line wire 62, and wire 63 back to battery E. As a result, fluid will now be supplied to cylinder 9 of motor M from the high 45 pressure system. When the pressure of the fluid in motor M increases to 60 pounds per square inch, contact 28-28^b of pressure responsive device P^{40-60} will become closed and will complete the previously described circuit for relay C so 50 that relay C will then become energized. The energization of relay C, however, has no immediate effect on the apparatus under these conditions. When the pressure of the fluid in motor M increases to 70 pounds per square inch, contact 28-28^a of pressure responsive device P^{70-80} 55 will open and will deenergize valve V^2 , and if the pressure of the fluid in motor M increases to 80 pounds per square inch, so that contact 28-28^b of pressure responsive device P^{70-80} becomes closed, a circuit will become completed for valve 60 V^2 which passes from battery D through wires 65 and 66, line wire 67, wire 83, contact 28-28^b 65 of pressure responsive device P^{70-80} , line wire 86, contact 29⁴ of lever L, wires 85, 71 and 72, asymmetric unit 73 in its low resistance direction, 70 front contact 48-48^a of relay C, wire 80, contact 29⁴⁻⁵ of lever L, wire 79, line wire 78, winding 20 of valve V^2 , wire 76, line wire 77, and wire 56 back to battery D. Valve V^2 will therefore 75 become energized and will connect the cylinder 9 of motor M with the pipe 24. When the cylinder 9 becomes connected with the pipe 24 under these conditions, the pressure of the fluid in the cylinder will, of course, be above that of the pressure of the fluid in the pipe 24, so that fluid will be vented from the motor into

the low pressure distribution system, thus rendering the exhaust fluid from the motor available for later use. It will be apparent, therefore, that if lever L is moved to its p^4 position directly from its p^3 position, fluid pressure will be supplied to cylinder 9 of motor M from the low pressure distribution system until the pressure of the fluid in the motor increases to 40 pounds per square inch after which fluid will be supplied to the motor from the high pressure distribution system. It will also be apparent that when the lever occupies its p^4 position, if the pressure of the fluid in the motor increases to 80 pounds per square inch, fluid will be vented from the motor into the low pressure distribution system.

I will next assume that the operator, instead of moving lever L from its p^3 position to its p^4 position, moves the lever directly from its p^1 or p^2 position to its p^4 position. Under these conditions, when the lever reaches its p^4 position, the pressure of the fluid in motor M will be below 40 pounds per square inch, so that relay B will still be energized and as a result, a circuit will then be completed for valve V^2 which passes from battery E through wire 56, line wire 77, wire 76, winding 20 of valve V^2 , line wire 78, wire 79, contact 29⁴⁻⁵ of lever L, wire 80, front contact 44-44^b of relay B, asymmetric unit 81 in its low resistance direction, wires 72, 71 and 85, contact 29⁴ of lever L, line wire 86, contact 28-28^a of pressure responsive device P^{70-80} , wire 61, line wire 62, and wire 63 back to battery E. Valve V^2 will therefore become energized and will admit fluid to cylinder 9 of motor M from the low pressure source until the pressure in the motor builds up to 40 pounds per square inch, at which time contact 28-28^a of pressure responsive device P^{40-60} will open and will deenergize relay B, thus deenergizing valve V^2 . The deenergization of relay B will also complete the previously described circuit for valve V^3 including back contact 44-44^b of relay B, so that valve V^3 will then become energized. When valve V^3 becomes energized, the apparatus will subsequently function in the same manner as it does after this valve becomes energized when lever L is moved to its p^4 position from its p^3 position.

If the operator moves lever L from its p^4 position to its p^5 position, valve V^3 will become energized and will thereafter remain energized by virtue of a circuit which passes from battery E through wire 56, line wire 77, winding 20 of valve V^3 , asymmetric unit 84 in its low resistance direction, line wire 74, back contact 44-44^b of relay B, asymmetric unit 81 in its low resistance direction, wire 72, contact 29⁵ of lever L, and wire 63 back to battery E. Under these conditions, therefore, fluid will be continuously supplied to cylinder 9 of motor M from the high pressure source so that the braking bars will exert their maximum braking force.

If when lever L is moved to its p^5 position the lever had previously occupied its p^1 or p^2 position, and it is moved directly to its p^5 position without stopping the lever in its p^3 or p^4 position, the apparatus will function in the same manner as was previously described when the lever was moved from its p^1 or p^2 position to its p^4 position, up to the time when relay B becomes deenergized, whereupon the circuit last traced for valve V^3 will become completed. When this circuit becomes completed, valve V^3 will, of course, become energized, and will subsequently remain energized as long as the lever remains in its p^5 position, in the

same manner as when the lever was moved to its p^5 position from its p^4 position. If, when lever L occupies its p^5 position, so that the braking bars are exerting their maximum braking force, the operator wishing to reduce the braking force exerted by the braking bars, moves lever L to its p^2 position, the circuit just described for valve V³ will become interrupted, and valve V² will become energized over a circuit which passes from battery D through wires 65 and 66, line wire 67, wire 83, contact 28—28^b of pressure responsive device P^{20—30}, line wire 82, contact 29² of lever L, wires 85, 71 and 72 asymmetric unit 73 in its low resistance direction, front contact 48—48^a of relay C, wire 80, contact 29^{1—2} of lever L, wire 79, line wire 78, winding 20 of valve V², wire 76, line wire 77, and wire 56 back to battery D. Fluid will therefore now be vented from motor M into the low pressure system in a manner which will be readily understood from the foregoing. When the pressure of the fluid in motor M decreases to 60 pounds per square inch, contact 28—28^b of pressure responsive device P^{40—60} will become opened and will deenergize relay C. When this happens, the circuit which was previously closed for valve V² at front contact 48—48^a of relay C will become interrupted, and valve V² will therefore become deenergized, thus disconnecting cylinder 9 of motor M from pipe 24 and hence from the low pressure distribution system. Furthermore, when relay C becomes deenergized, the previously described circuit for valve V¹ including contact 48—48^b of relay C, contact 28—28^b of pressure responsive device P^{20—30} and contact 29² of lever L will become closed, so that valve V¹ will become energized and will exhaust fluid from motor M to atmosphere. Valve V¹ will then continue to exhaust fluid from motor M to atmosphere until the pressure in the motor decreases to 30 pounds per square inch, at which time contact 28—28^b of pressure responsive device P^{20—30} will open and will deenergize valve V¹. The apparatus will then function in the same manner as was previously described when lever L was moved from its p^1 to its p^2 position. If, when lever L occupies its p^5 position, the operator instead of moving the lever to its p^2 position to decrease the braking force exerted by the brake bars, moves the lever to its p^1 position in order to restore the braking bars to their non-braking positions, valve V² will initially become energized over a circuit which passes from battery D through wires 65 and 66, contact 29¹ of lever L, wires 70, 71 and 72, asymmetric unit 73 in its low resistance direction, front contact 48—48^a of relay C, wire 80, contact 29^{1—2} of lever L, wire 79, line wire 78, winding 20 of valve V², wire 76, line wire 77, and wire 56 back to battery D. The energization of valve V² under these conditions will cause fluid to be vented from cylinder 9 of motor M into the low pressure distribution system in the manner previously described until the pressure in the cylinder decreases to 60 pounds per square inch at which time the resultant opening of contact 28—28^b of pressure responsive device P^{40—60} will deenergize relay C, thus deenergizing valve V². The deenergization of relay C under these conditions will also complete the previously described circuit for valve V¹ including contact 29¹ of lever L, and back contact 48—48^b of relay C, so that relay C will then become energized and will vent the remainder of the fluid from cylinder 9 of motor M to atmosphere. When the pressure of the fluid in motor M decreases to 40 pounds per square inch, contact 28—28^b of pressure responsive device P^{40—60} will close, thus causing relay B to again become energized. The energization of relay B under these conditions, however, will have no effect on the braking apparatus. As the pressure of the fluid in motor M continues to decrease, the braking bars will gradually return to their non-braking positions, and when the braking bars reach their non-braking positions, all parts of the apparatus will then be restored to the positions in which they are illustrated in the drawings.

It should be pointed out that while in describing the operation of the apparatus shown in Fig. 2, I have only described the operation which takes place during a few of the possible movements of lever L, the operation of the apparatus for the remainder of these movements is substantially the same as that for the described movements, and it is believed, therefore, that this operation will be readily understood from the drawings without further description.

Although I have herein shown and described only two forms of railway braking apparatus embodying my invention, it is understood that various changes and modifications may be made therein within the scope of the appended claims without departing from the spirit and scope of my invention.

Having thus described my invention, what I claim is:

1. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a relay, means for energizing said relay when and only when the pressure of the fluid in said motor is below a predetermined pressure, and means for admitting fluid to said motor from said first or said second pipe according as said relay is energized or deenergized.

2. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a relay, means for energizing said relay when and only when the pressure of the fluid in said motor is below a predetermined pressure, and means controlled by said relay for selectively controlling said two magnet valves.

3. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a relay, means for energizing said relay when and only when the pressure of the fluid in said motor is below a predetermined pressure, and means for at times energizing said first or said second

- necting said motor with atmosphere, means for at times energizing said first or said second valve according as the pressure of the fluid in said motor is then below or above a first predetermined pressure which is somewhat below the pressure of said low pressure source, and means for at other times energizing said second or said third valve according as the pressure of the fluid in said motor is below or above a second predetermined pressure which is somewhat higher than the pressure of said low pressure source. 10
14. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a first relay, 20 means for energizing said first relay when and only when the pressure of the fluid in said motor is below a first predetermined pressure, a second relay, means for energizing said second relay when and only when the pressure of the fluid in said motor is above a second predetermined pressure which is somewhat higher than said first predetermined pressure, and means controlled by said two relays for selectively energizing said three magnet valves. 25
15. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a first relay, 30 means for energizing said first relay when and only when the pressure of the fluid in said motor is below a first predetermined pressure, a second relay, means for energizing said second relay when and only when the pressure of the fluid in said motor is above a second predetermined pressure which is somewhat higher than said first predetermined pressure, and means controlled by said two relays for selectively energizing said three magnet valves. 35
16. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a first relay, 40 means for energizing said first relay when and only when the pressure of the fluid in said motor is below a first predetermined pressure, a second relay, means for energizing said second relay when and only when the pressure of the fluid in said motor is above a second predetermined pressure which is somewhat higher than said first predetermined pressure, and means controlled by said two relays for selectively energizing said three magnet valves. 45
17. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a first contact responsive to the pressure of the fluid in said motor and adjusted to open at a first predetermined pressure, a second contact responsive to the pressure of the fluid in said motor and adjusted to become closed at a second predetermined pressure which is somewhat higher than said first predetermined pressure, a first relay controlled by said first contact, a second relay 50 controlled by said second contact, and means controlled by said two relays for selectively controlling said three magnet valves. 55
18. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a first relay, 60 means for energizing said first relay whenever the pressure of the fluid in said motor is below a first predetermined pressure which is somewhat lower than the pressure of said low pressure source, a second relay, means for energizing said second relay whenever the pressure of the fluid in said motor is above a second predetermined pressure which is somewhat higher than the pressure of said low pressure source, a manually operable lever provided with two contacts, a first circuit for said first magnet valve including the one contact of said lever and a front contact of said second relay, a first circuit for said third magnet valve including the one contact of said lever and a back contact of said second relay, a second circuit for said first magnet valve including the other contact of said lever and a front contact of said first relay, and a circuit for said second magnet valve including said other contact of said lever and a back contact of said first relay. 65
19. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a first relay, 70 means controlled by the pressure of the fluid 75

means for energizing said first relay whenever the pressure of the fluid in said motor is below a first predetermined pressure which is somewhat lower than the pressure of said low pressure source, a second relay, means for energizing said second relay whenever the pressure of the fluid in said motor is above a second predetermined pressure which is somewhat higher than the pressure of said low pressure source, a manually operable lever provided with two contacts, a first contact responsive to the pressure of the fluid in said motor and adjusted to open at a third predetermined pressure which is higher than said second predetermined pressure, a second contact responsive to the pressure of the fluid in said motor and adjusted to close at a fourth predetermined pressure which is higher than said third predetermined pressure, a first circuit for said first magnet valve including one of said lever contacts and a front contact of said second relay, a first circuit for said third magnet valve including said one lever contact and a back contact of said second relay; a second circuit for said first magnet valve including the other lever contact, said first pressure responsive contact, and a front contact of said first relay; a third circuit for said first magnet valve including said other lever contact, said second pressure responsive contact, and a front contact of said second relay, and a circuit for said second magnet valve including said other lever contact, said first pressure responsive contact, and a back contact of said first relay.

20. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a relay, means for energizing said relay when the pressure of the fluid in said motor is above a predetermined pressure which is somewhat higher than the pressure of said low pressure source, means for at times energizing said second magnet valve, a manually operable contact, a circuit for said first magnet valve including said manually operable contact and a front contact of said relay, and a circuit for said third magnet valve including said manually operable contact and a back contact of said relay.

21. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a first relay, means for energizing said first relay whenever the pressure of the fluid in said motor is below a first predetermined pressure which is somewhat lower than the pressure of said low pressure source, a second relay, means for energizing said

second relay whenever the pressure of the fluid in said motor is above a second predetermined pressure which is somewhat higher than the pressure of said low pressure source, a first contact responsive to the pressure of the fluid in said motor and adjusted to open at a third predetermined pressure which is below said first predetermined pressure, a second contact responsive to the pressure of the fluid in said motor and adjusted to close at a fourth predetermined pressure which is between said first and third predetermined pressures, a manually operable contact, means including a back contact of said first relay for at times energizing said second magnet valve; a first circuit for said first magnet valve including said manually operable contact, said first pressure responsive contact, and a front contact of said first relay, a second circuit for said first magnet valve including said manually operable contact, said second pressure responsive contact, a front contact of said second relay; and a circuit for said third magnet valve including said manually operable contact, said second pressure responsive contact and a back contact of said second relay.

22. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a first relay, means for energizing said first relay whenever the pressure of the fluid in said motor is below a first predetermined pressure which is somewhat lower than the pressure of said low pressure source, a second relay, means for energizing said second relay whenever the pressure of the fluid in said motor is above a second predetermined pressure which is somewhat higher than the pressure of said low pressure source, a third magnet valve effective when energized for connecting said motor with atmosphere, a relay, means for energizing said relay when the pressure of the fluid in said motor is above a predetermined pressure which is somewhat higher than the pressure of said low pressure source, means controlled by a back contact of said first relay for at times energizing said second magnet valve, means controlled by a front contact of said first relay for at times energizing said first magnet valve, means controlled by a front contact of said second relay for at other times energizing said first valve, means controlled by a back contact of said second relay for at times energizing said third valve, a manually operable contact, and a circuit for said first valve controlled solely by said manually operable contact.

23. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a first relay, means for energizing said first relay whenever the pressure of the fluid in said motor is below a first predetermined pressure which is somewhat lower than the pressure of said low pressure source, a second relay, means for energizing said second relay whenever the pressure of the fluid in said motor is above a second predetermined pressure which is somewhat higher than the pressure of said low pressure source, a third magnet valve effective when energized for connecting said motor with atmosphere, a relay, means for energizing said relay whenever the pressure of the fluid in said motor is above a third predetermined pressure which is between said first and second predetermined pressures, a manually operable contact, means including a back contact of said first relay for at times energizing said second magnet valve; a first circuit for said first magnet valve including said manually operable contact, said first pressure responsive contact, and a front contact of said first relay, a second circuit for said first magnet valve including said manually operable contact, said second pressure responsive contact, a front contact of said second relay; and a circuit for said third magnet valve including said manually operable contact, said second pressure responsive contact and a back contact of said second relay.

- source, a second relay, means for energizing said second relay whenever the pressure of the fluid in said motor is above a second predetermined pressure which is somewhat higher than the pressure of said low pressure source, a first contact responsive to the pressure of the fluid in said motor and adjusted to open at a third predetermined pressure which is higher than said second predetermined pressure and a second contact responsive to the pressure of the fluid in said motor and adjusted to close at a fourth predetermined pressure which is higher than said third predetermined pressure, a manually operable contact; a first circuit for said first magnet valve including said manually operable contact, said first pressure responsive contact, and a front contact of said first relay; a second circuit for said first magnet valve including said manually operable contact, said first pressure responsive contact, and a back contact of said first relay; and means for at times energizing said third magnet valve when and only when said manually operable contact is open.

24. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve effective when energized for connecting said motor with said first pipe, a second magnet valve effective when energized for connecting said motor with said second pipe, a third magnet valve effective when energized for connecting said motor with atmosphere, a first relay, means for energizing said first relay whenever the pressure of the fluid in said motor is below a first predetermined pressure which is somewhat lower than the pressure of said low pressure source, a second relay, means for energizing said second relay whenever the pressure of the fluid in said motor is above a second predetermined pressure which is somewhat higher than the pressure of said low pressure source, a manually operable contact, a circuit for said first magnet valve including said manually operable contact and a front contact of said first relay, a circuit for said second magnet valve including said manually operable contact and a back contact of said first relay, and means including a back contact of said second relay and effective when neither of said circuits is closed for at times energizing said third magnet valve.

25. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a third magnet valve for connecting said motor with atmosphere, a first contact responsive to the pressure of the fluid in said motor and adjusted to open at a first predetermined pressure which is below the pressure of the fluid in said first pipe, a second contact responsive to the pressure of the fluid in said motor and adjusted to become closed at a second predetermined pressure which is above

the pressure of the fluid in said first pipe, a first and a second relay, three wires, a first source of electromotive force connected with a first and a second one of said wires, a second source of electromotive force connected with said first wire and the third wire, means including a first asymmetric unit and said first pressure responsive contact for connecting said first relay with said first and second wires, means including a second asymmetric unit and said second pressure responsive contact for connecting said second relay with said first and third wires, said two asymmetric units being disposed in opposite directions with respect to said first wire, and means controlled by said two relays for selectively controlling said magnet valves.

26. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a third magnet valve for connecting said motor with atmosphere, a first relay, means for energizing said first relay when the pressure of the fluid in said motor is below a first predetermined pressure which is lower than the pressure of said low pressure source, a second relay, means for energizing said second relay when the pressure of the fluid in said motor is above a second predetermined pressure which is higher than the pressure of said low pressure source, three wires, a first source of electromotive force connected with a first and a second one of said wires, a second source of electromotive force connected with said first wire and the third wire, a lever provided with a plurality of contacts which may be selectively operated by manipulation of said lever, a first contact responsive to the pressure of the fluid in said motor and adjusted to become opened at a predetermined pressure, a second contact responsive to the pressure of the fluid in said motor and adjusted to become closed at a pressure which is somewhat higher than the pressure at which said first contact becomes opened, four asymmetric units, means including a first contact of said lever, a first one of said asymmetric units, a back contact of said second relay and a second one of said asymmetric units for connecting said third magnet valve with said second and first wires; means including said first contact of said lever, said first asymmetric unit, a front contact of said second relay and a second contact of said lever for connecting said first magnet valve with said second and first wires; means including a front contact of said first relay, a third one of said asymmetric units, a third contact of said lever, and said first pressure responsive contact for connecting said first magnet valve with said first and said third wires; means including said second pressure responsive contact, said third contact of said lever, said first asymmetric unit, said back contact of said second relay and said second asymmetric unit for connecting said third magnet valve with said second and first wires; means including said second pressure responsive contact, said third contact of said lever, said first asymmetric unit and said front contact of said second relay for connecting said first magnet valve with said second and first wires; and means including the

fourth asymmetric unit, a back contact of said first relay, said third asymmetric unit, and a fourth contact of said lever for connecting said second magnet valve with said first and third line wires.

5 27. Railway braking apparatus comprising a braking bar extending parallel to a track rail, a fluid pressure motor for moving said braking bar toward the track rail into braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a third magnet valve for connecting said motor with atmosphere, a first contact responsive to the pressure of the fluid in said motor and adjusted to open at a first predetermined pressure which is below the pressure of the fluid in said first pipe, a second contact responsive to the pressure of the fluid in said motor and adjusted to open at a second predetermined pressure which is above
